UNITED STATES PATENT OFFICE

FREDERICK A. PRAHL, OF NEW YORK, N. Y., AND HENRY A. FINK, OF CHICAGO, ILLINOIS, ASSIGNORS TO CONTINENTAL CAN COMPANY, INC., OF NEW YORK, N. Y., A CORPORATION OF NEW YORK

MACHINE FOR COATING CAN ENDS

Application filed February 1, 1928. Serial No. 251,092.

The invention relates to new and useful improvements in machines for coating can ends, and more particularly to a machine for applying a sealing material to the portion of the can end which is rolled into a double seam when the end is joined to the can body.

An object of the invention is to provide a machine for applying a sealing material to a can end wherein the coating is applied to the end by a nozzle disposed beneath the can end so that when the supply of the sealing material to the nozzle is cut off, there will be no dripping or draining of the sealing material on to the can end.

A further object of the invention is to provide a machine of the above type with means for giving an initial curl to the edge of the can end during the coating of the same.

In the drawings which show by way of illustration one embodiment of the invention—

Figure 1 is a sectional view through a machine embodying the improvement;

Figure 2 is an enlarged sectional view through the nozzle;

Figure 3 is a detail in plan showing more or less diagrammatically the means for controlling the valve, which in turn controls the discharge of the sealing material from the nozzle;

Figure 4 is an enlarged sectional view showing the can end and the nozzle with the material flowing from the nozzle on to the can end;

Figure 5 is a view similar to Figure 4, but showing the discharge of the sealing material from the nozzle, cut off;

Figure 6 is a side view of the machine shown in Figure 1 with parts broken away to show the means for giving an initial curl to the can end during the coating thereof;

Figure 7 is a plan view of the mechanism for moving the curling roll;

Figure 8 is a detail showing the can end before giving an initial curl thereto; and

Figure 9 is a view on an enlarged scale showing a portion of the chucks, the can

end, and the curling roll for giving the initial curl to the edge of the can end.

The invention is directed to a machine for coating can ends of the type disclosed in the patent to Robinson & Coyle No. 1,172,049, granted February 15, 1916. In this patent, a can end to be coated is placed between two cooperating rotating chucks with the channel to be coated facing downward. The sealing material is applied by means of a roll which makes rolling contact with the bottom of the channel in the can end, and thus applies a coating thereto. There is a limitation as to the character of sealing material which may thus be applied

to the can end, and also a limitation as to the amount of sealing material that may be applied. The present invention is directed to an entirely different means of applying a sealing material to the can end. In the machine disclosed, the can end is placed between chucks and rotated after the manner described in the patent to Robinson & Coyle.

The coating rolls, however, have been replaced by a different type of mechanism for applying the sealing material to the channel in the can end. Located directly beneath the can end channel is a nozzle. This nozzle projects into the channel, but is spaced from the bottom of the channel.

The sealing material is delivered to the nozzle from a supply tank by air pressure. The nozzle is provided with a valve operating at the discharge end of the nozzle for closing the same. The amount of sealing material applied to the can end will depend upon the length of time which the valve is open. After the can end is placed, and while it is rotating, the nozzle is opened, and the sealing material forced therefrom in a jet against the bottom of the channel. The nozzle sets back from the outer side of the channel, and the material as it strikes the bottom of the channel, due to the centrifugal force operating thereon, will flow outward and completely fill the channel lining the curled edge of the can end.

The machine is also provided with means for forming an initial curl on the can end during the rotating of the can end for coat-

ing the same. This is accomplished by a curling roll having a curved annular there-in, which curling roll is moved radially of the chucks into engagement with the edge 5 of the can end. This curling roll is timed in its movement so as to engage the edge of the can end giving thereto a curved formation which is the beginning of the usual curl formed on a can end to aid in the forming of the double seam. This initial curl 10 on the can end aids in the flow of the sealing material to the extreme edge of the can end and prevents the sealing material from being thrown from the can end during the 15 rotation thereof.

Referring more in detail to the drawings, the invention is shown as applied to a can end coating machine which includes a supporting frame 1 having a central shaft 2. 20 Mounted to rotate about this central shaft 2 is a sleeve 3 carrying a can end feeding member 4. This sleeve 3 is given an intermittent movement after the manner described in the patent. The shaft 2 is rotated by a suitable gear connection with the main shaft 5.

Mounted in the frame of the machine is an upper chuck spindle 6 carrying a chuck 7. Also mounted in the frame is a lower chuck spindle 8 carrying a lower chuck 9. These chuck spindles are in axial alignment, and both spindles are mounted so that they may be moved up and down. The upper chuck spindle 6 carries a sprocket gear 10 which is rotated by a sprocket chain connection with a sprocket gear 11 on the upper end of the shaft 2. Through this sprocket gear connection to the shaft, the upper chuck is rotated, and when the upper chuck 35 engages a can end placed on the lower chuck, then the lower chuck will rotate therewith. This imparts a rotation to the can end clamped between the chucks. The can end is placed between the chucks by the 40 intermittently rotating can end feeding device 4. The can end is indicated in the drawings at C. The lower chuck spindle is mounted for free rotation, and is held raised by means of a spring 12, a stop collar 13 45 limiting the upward movement of the chuck spindle. When the lower chuck is at its extreme upper position, it is on a level so that the intermittent can end feed 4 will move the can end on to the lower chuck. The 50 upper chuck spindle is raised and lowered in its supporting bearing by means of a lever 14 pivoted at 15 and connected to a member 16 which oscillates the lever. The member 16 carries a roller 16^a running in a cam groove 16^b in a disc 16^c on the shaft 5. These parts are shown in Fig. 1. The outer 55 end of the lever 14 is connected to the chuck spindle so that the chuck spindle is free to be rotated. It is also connected to the spindle so that the spindle may be shifted, and

thus properly set in its attachment to the lever. The up and down movements of the chuck are so timed relative to the feed of the can end that the upper chuck is raised, permitting the can end to be moved underneath the same and placed on the lower chuck, after which the upper chuck moves down on to the lower chuck and will depress the lower chuck to a certain extent. The rotation of the chucks with the can end 70 clamped between the same, thus produces a rotation of the can end. Directly beneath the channel in the can end and at one side of the lower chuck spindle is a coating nozzle 17. This coating nozzle is shown in detail in Fig. 2. The nozzle is mounted in the supporting bracket 18 attached to the frame of the machine. The nozzle includes a supporting sleeve 19 into which is threaded an extension sleeve 20. A delivery nozzle 21 is attached to this extension sleeve by a nut 22. The delivery nozzle has a relatively small delivering opening 23. Located inside of the sleeves is a needle valve 24 provided with a tapered end 25 adapted to engage a tapered seat at the inside of the delivery nozzle 21 and at the opening 23. Attached to the needle valve is a flexible diaphragm 26. The needle valve is adjustably attached to this diaphragm. 80

This needle valve is connected to a valve stem 27. The valve stem is attached to a guiding piston 28 and is adapted to slide freely in the sleeve 19. A spring 29 bears against the piston 28 and against the lower end of the sleeve which is closed, except for the opening through which the stem passes. This spring normally raises the valve stem and forces the valve into contact with the seat at the nozzle end, thus closing the same. 100 The sealing material is supplied to the nozzle from a suitable storage receptacle by a connection with a pipe 30 (see Fig. 1), which is threaded into an opening 31 in the wall of the extension sleeve 17. Thus it is 105 that the sealing material is delivered under air pressure to the chamber 32. When the valve is open, the sealing material will be squirted or sprayed out of the end of the nozzle and in an upward direction. When, however, the needle valve is closed, then the supply is cut off, and the discharge ceases 110 at once.

The machine is also provided with means for giving an initial curl to the can end while the same is being rotated for the coating. This curling means is shown in Figures 7 to 9 inclusive. It includes a curling roll 50 shown on an enlarged scale in Fig. 9. This curling roll 50 is provided with a curved 125 annular groove 51. The can end is indicated at C. It is shown as clamped between the chucks 7 and 9. The curling roll is moved radially of the chucks into engagement with the can end C while the can end 130

is being rotated. The curved curling groove 51 will give an initial curl to the can end as indicated at C¹. This curling roll is carried by a bar 52 which is mounted so that it can slide in suitable ways carried by the frame of the machine. This bar slides in a line which passes through the center of rotation of the chucks and thus it is that the curling roll is moved radially of the chucks. This curling roll is mounted for free rotation and when it is moved up into engagement with the edge of the can end it will rotate and gradually turn the edge into a well curved initial curl. The bar carrying the curling roll is moved endwise by means of a lever 53. This lever is forked at its lower end and said forked end straddles a pin 54 which is attached to the bar 52. The cover plate is slotted at 54^a and the pin 54 projects through said slot. The lever is pivoted at 55 to the side frame of the machine and projects above said pivot. The upper end of the lever is forked as indicated by dotted lines at 56. A pin 57 carried by a bracket 58 engages said upper forked end of the lever 53. This bracket 58 is attached to a slide rod 59. The slide rod is mounted so that it may be reciprocated in suitable bearing lugs 60, 60 which are attached to the side frame of the machine. This slide bar is attached to a link 61 which in turn is pivoted at 62 to an arm 63 mounted on the upper end of a vertical shaft 64. This vertical shaft 64 is mounted in suitable bearings in the frame and is oscillated by a slide rod 65 which is moved endwise by means of a roll 66 mounted thereon cooperating with an eccentrically set member 67 on the main shaft 68. A spring 69 surrounding the slide rod 59 normally forces the rod to the left as viewed in Fig. 6. This causes a movement of the upper end of the lever 53 to the left and a movement of the lower end of this lever to the right. Thus it is that the spring 65 yieldingly holds the curling roll retracted. When the shaft 64 is oscillated in the proper direction then the slide bar 59 is moved to the right as viewed in Figure 6 and this will positively force the curling roll into engagement with the edge of the can end. The curling roll is timed and operated so as to be held a sufficient length of time in engagement with the can end to cause a well defined initial curl on the can end. This initial curl also sizes up the can end to a predetermined size depending upon the extent of movement imparted to said curling roll.

The machine is also provided with a curling roll 69^a located at the curling station C (Figs. 6 and 7) which is of the type shown in the patent to Robinson & Coyle referred to above. This curling roll is likewise operated by the oscillations of the shaft 64. This curling roll forms the final part of what might be called the preliminary curl. This

preliminary curl on the can end protects the coating material and also aids in the proper formation of the double seam insuring that the can end when turned into the double seam is interfolded and locked with the flange on the can body. This curling roll 50 might be called the auxiliary curling roll as it performs its function first and at the same time when the coating is applied to the can end. In Figs. 6 and 7 the coating device is removed from the machine for the sake of clearness, but it is clearly shown in Fig. 1. The coating nozzle is disposed directly in front of the center line of the chucks as viewed in this Fig. 6. In Figs. 8 and 9 there is shown the can end as it comes from the die press and the edge thereof is shown as bent away from the outer face of the end so as to provide the channel c. There is the metal at the outer edge of this channel that is turned into the initial curl by the curling roll 50.

The sealing material is indicated at S. In Fig. 4 the valve is shown as open and the nozzle is spraying or squirming the sealing compound against the bottom of the channel c in the can end. It is noted that the nozzle is located a little up in the channel but is at the same time spaced from the bottom of the channel. It is also located a little toward the inner side of the channel. As a result the sealing material is sprayed or squirted against the bottom of the channel so as to form a clean cut coating line c². Inasmuch as the end is rotated when the sealing material is thrown against the same the centrifugal force acting thereon will cause said sealing material to flow outwardly along the wall of the channel and all the way around the curled outer edge of the channel. When the extreme edge of the can is curved so that the wall of the channel leads directly into the curved inner face of the curl the sealing material will flow all the way around freely to the edge of the can end. If the can end is not curved but shaped as shown in Fig. 8 then the sealing material is likely to be thrown from the can end. There is an advantage, therefore, in curling the can end at the same time or prior to the coating of the same. This initial curl is formed in the present apparatus during the coating and the initial curl serves in a measure as a dam to stop the outward flow of the sealing material. It is also coated at the extreme edge of the curled portion. When the valve is closed, the discharge of the sealing material at once ceases, and there will be no dripping or draining of the sealing material on to the can end. As soon as the pressure forcing the sealing material out of the nozzle ceases, there can be no possible accumulation of the sealing material at the end of the nozzle through leakage or otherwise, which will continue to drop or drip on to the can end.

Prior to our invention, nozzles have been used for coating can ends with the channel facing upward and the nozzle above the can end. In such a type of coating machine, there is always more or less of a drip or a string of coating material which is dragged across the face of the can end as it is moved from the chuck. By our improved arrangement of the discharge nozzle, this drawing of strings of sealing material across the face of the can end is entirely avoided. Furthermore, the sealing material in just the proper amount may be applied to the channel, and will completely coat the channel all the way around to the outer edge of the curled portion of the can end.

The valve is closed as above noted, by means of the spring 29. It is opened to permit the discharge of the sealing material by a control mechanism which includes a lever 33. This lever has its inner end forked at 33^a (Fig. 3), which forked end engages the valve stem. The outer end of the lever 33 is directly above and rests on the arm 34 carried by the shaft 35. This shaft 35 carries a second arm 36 which is connected to a rod 37. The rod 37 is forked at 37^a, 37^b so as to straddle an operating cam 38. A roller 39 pivotally supported by the forks 37^a, 37^b of the rod 37 bears on said cam. The cam is mounted on the main shaft 5. As the main shaft rotates, this cam will cause the rod to be raised and lowered, and this will oscillate the shaft 35 which will raise and lower the arm 34. A spring 40 normally forces the rod 37 in a downward direction and holds the roller 39 in contact with the cam 38. The lever 33 intermediate its ends is fulcrumed on a standard 41. This standard 41 is capable of sliding vertically in a bracket 42. A spring 43 normally holds the standard in its lowermost position, and the end of the lever 33 in engagement with the arm 34. When the standard is free to move in its guiding bracket, the oscillations of the arm 34 will raise and lower the extreme left-hand end of the lever 33, as viewed in Fig. 1, and this will impart no movement to the valve stem. A pin 44 is provided for locking this standard so as to hold it from movement, and when the standard is locked so that it cannot move vertically, then it becomes a central fulcrum for the lever 33 on which the lever will swing. When the lever swings on its fulcrum, the right-hand end of the lever will be depressed by the upward movement of the arm 34, and this will cause the opening of the valve. The valve will be held open until the cam 38 swings the arm 34 downward, at which time the spring can close the valve.

The pin 44 which locks the standard and holds the same in fixed position, is controlled by a shaft 45 which carries at its outer end an arm 46. The arm 46 extends under-

neath a control rod 47 which extends up through the lower chuck spindle. This rod projects beyond the limiting collar 13, and a spring 48 will hold the rod in its lowermost position, except as it is controlled by the arm 46. The rod 47 at its upper end is provided with a head 49. This head is located centrally of the lower chuck. When there is no can end placed on the lower chuck, the upper chuck makes engagement with the lower chuck and will depress it. The rod 47 coming in engagement with the arm 46 will be raised, and there is nothing to restrain its upward movement, so that the arm 46 is not depressed sufficiently to cause the pin to grip and hold the standard from movement. When, however, a can end is placed on the lower chuck and clamped thereagainst by the upper chuck, the downward movement of the two chucks with the end clamped between them, will cause a downward movement of the rod 47. The head 49 on the rod 47 lies close beneath the can end, and the can end will prevent it from movement relative to the lower chuck. Therefore, the rod 47 will move downward with the lower chuck and the lower end of the rod will engage the arm 46 which will oscillate the shaft 45 and cause the pin 44 to grip the standard 41, thus forming a fixed fulcrum support on which the lever 33 can oscillate to open the needle valve (see Fig. 3).

From the above it will be apparent that we have provided a coating machine for applying a sealing material to the channel of a can end, wherein just the right amount of sealing material may be coated on the face of the channel, and the channel supplied with a coating from the desired inner position of the coating, all the way to the extreme end of the curled edge of the can end. It will further be noted that we have provided a coating machine wherein there is no dripping or forming of strings of coating material which are carried on to the can end as it is moved from the chuck which would result in unsanitary conditions.

It is obvious that minor changes in the details of construction and arrangement of the parts may be made without departing from the spirit of the invention as set forth in the appended claims.

Having thus described the invention, what we claim as new and desire to secure by Letters-Patent, is—

1. A can end coating machine including in combination, upper and lower chucks rotating about a common axis, means for giving said chucks a relative movement toward and from each other to clamp and release a can end, with the channel to be coated facing downwardly, a nozzle located beneath the can end and disposed so as to discharge a coating of sealing material against the

under face of the channel, a pipe attached to said nozzle through which sealing material may be supplied to the nozzle under pressure, a valve mechanism for controlling the discharge of the sealing material from said nozzle, and means for rendering said valve mechanism ineffective when no can end is positioned for coating.

5. A can end coating machine including in combination, upper and lower chucks rotating about a common axis, means for giving said chucks a relative movement toward and from each other to clamp and release a can end, with the channel to be coated facing downwardly, a nozzle located beneath the can end and disposed so as to discharge a coating of sealing material against the under face of the channel, a pipe attached to said nozzle through which sealing material may be supplied to the nozzle under pressure, a valve mechanism for controlling the discharge of the sealing material from said nozzle, and means for rendering said valve mechanism ineffective when no can end is positioned for coating, said valve mechanism including a rod located within the nozzle and adapted to close the nozzle at the extreme delivery end thereof.

3. A can end coating machine including in combination, upper and lower chucks rotating about a common axis, means for giving said chucks a relative movement toward and from each other to clamp and release a can end, with the channel to be coated facing downwardly, a nozzle located beneath the can end and disposed so as to discharge a coating of sealing material against the under face of the channel, a pipe attached to said nozzle through which sealing material may be supplied to the nozzle under pressure, a valve mechanism for controlling the discharge of the sealing material from said nozzle, and means for rendering said valve mechanism ineffective when no can end is positioned for coating, said nozzle being disposed within the channel during coating but spaced from the bottom of the channel and adjacent the inner side of the channel.

4. A can end coating machine including in combination, upper and lower chucks rotating about a common axis for clamping and rotating a can end; a coating nozzle disposed so as to discharge a coating of sealing material against the face of the channel in the can end; a pipe connected to said nozzle through which sealing material may be supplied to the nozzle under pressure, a valve mechanism controlling the discharge of the sealing material from the nozzle, a curling roll for forming an initial curl in the edge of the can end disposed so as to engage said can end while the same is being rotated for coating, and means for moving said curling roll into and out of engagement with the can end.

5. A can end coating machine including in combination, upper and lower chucks rotating about a common axis for clamping and rotating a can end with the channel to be coated facing downwardly, a nozzle located beneath the can end and disposed so as to discharge a coating of sealing material against the under face of the channel, a pipe connected to said nozzle through which sealing material may be supplied to the nozzle under pressure, a valve mechanism for controlling the discharge of the sealing material from said nozzle, a curling roll adapted to engage the edge of the can end while rotating for coating and forming an initial curl in the edge of the can end and means for moving said curling roll into and out of engagement with the can end.

In testimony whereof, we affix our signatures.

FREDERICK A. PRAHL.
